UNITED STATES PATENT OFFICE.

EDWIN G. IRELAND AND JOHN D. CLARK, OF CLAYBURN, BRITISH COLUMBIA,
CANADA.

HACKSAW.

1,394,174.

Specification of Letters Patent.

Patented Oct. 18, 1921.

Application filed November 1, 1920. Serial No. 421,034.

To all whom it may concern:

Be it known that we, EDWIN G. IRELAND and JOHN D. CLARK, citizens of the Dominion of Canada, residing at Clayburn, in the Province of British Columbia, Canada, have invented certain new and useful Improvements in Hacksaws, of which the following is a specification.

This invention relates to an improved 10 hack-saw frame, the improvements being particularly directed to the manner of connecting the saw blade to the frame whereby the blade may be set to any desired angle in relation to the plane of the frame and is 15 secured in such angular adjustment by the tension applied to the blade.

The invention is fully described in the following specification, reference being made to the drawings by which it is accompanied, in which:

Figure 1 is a side elevation of the saw.

Fig. 2, an end elevation in the direction of the arrow 2, and

Figs. 3 and 4 are enlarged details of the 25 manner of connecting the saw blade to the frame.

Figs. 5, 6 and 7 show a modification in the manner of adjustably connecting the saw to the frame.

In these drawings 2 represents the supporting frame of the saw, to one end of 30 which a handle 3 is secured. At the same end as the handle is attached a portion 4 projects below the handle to receive the saw blade connection, and above the handle at

35 5 to receive the rod 6 by which the saw is tightened in the frame in the manner to be described later.

To the outer end of the frame 2 a lever 8 40 is pivotally mounted at 7, the length of which lever corresponds to the distance between the saw connection 4 and the tightening rod connection 5 adjacent the handle. To the upper end of this lever 8 the tightening rod 6 is pin-connected at 9 and the other end of this rod is threaded where it passes through 5 to receive a wing nut 10.

The downwardly projecting end 4 of the frame 2 and the corresponding end 11 of the 45 lever 8 are conically bored to receive correspondingly coned bushings 12, which bushings are axially threaded to receive the stems 13 of jaw members 14 in which the ends of the saw 15 are connected by pins 16.

The end of each stem 13 where it passes

through the bushing 12 is provided with a lock nut 17 by which it is secured against rotation.

The ends of the saw 15 being secured in the jaw members 14 by the pins 16, the bushings 12 may be rotated in their supports 4 and 11 to set the plane of the saw blade to any desired angle in relation to that of the frame 2, and when the saw is drawn tight by means of the wing nut 10 on the end of 60 the tightening rod 6 and acting through the lever 8 that tightening effort secures the conical sleeves 12 against rotation from the position in which the blade has been adjusted. It will be noted that the jaw members 65 14 are secured against rotation in the conical sleeves 12 by the lock nuts 17.

To adjust the angle of the blade 15 it is only necessary to slacken the tightening rod 6 by means of the nut 10, and partially rotate the conical sleeves 12 to the desired adjustment for which purpose flats may be provided for a wrench across the larger end of each sleeve, as shown in Fig. 3, and on tightening the rod 6 the saw is secured in 70 80 the adjusted position.

The frame is one which rigidly supports the saw, the connection toward the handle being integral with the frame 2 and the lever 8, which forms the outer support, is 85 bifurcated to engage both sides of the end of the frame 2 adjacent the fulcrum with an ample bearing thereon, the tie rod 6 fitting at 9 between the open ends of the bifurcation.

We do not, however, desire to be confined to the particular construction of the saw frame as we regard the essential feature of the invention to be the conical support afforded each end connection of the saw blade, 90 where by the plane of the saw blade may be adjusted to any angle and secured in such angular adjustment by the tension applied to the blade.

Obviously the members 14, to which the 100 ends of the saw 15 are directly connected, instead of having the conical bushings 12 secured to them, may, as shown in Figs. 5, 6 and 7 of the drawings, have a flat tapered portion 20 adapted to fit the conical bore of 105 the members 4 and 11, in which case these members 14 may, when the saw is slack, be directly set to the desired angle, and will be secured in that adjustment when the saw is tightened.

Having now particularly described our invention, we hereby declare that what we claim as new and desire to be protected in by Letters Patent, is:

- 5 Means for connecting a hack-saw to its frame, said means comprising a member pinned connected to each end of the saw blade, each of said members having a threaded stem, a cone axially threaded on each stem with

10 the smaller dimension of the cone toward

the saw, means for locking the threaded stem in the cone, each cone member fitting a corresponding conical bearing in the saw frame, and means for applying tension to the saw blade through the cone bearings of 15 the saw connection.

In testimony whereof we affix our signatures.

EDWIN G. IRELAND.
JOHN D. CLARK.
